UNITED STATES PATENT OFFICE

161,642

POWER LAWN MOWER

Charles N. Phelps, Selma, Ala., assignor to Southland Mower Company, Inc., a corporation of Alabama

Application March 15, 1950, Serial No. 8,534

Term of patent 14 years

(Cl. D40—1)

To all whom it may concern:

Be it known that I, Charles N. Phelps, a citizen of the United States, residing at Selma, county of Dallas, State of Alabama, have invented a new, original, and ornamental Design for a Power Lawn Mower, of which the following is a specification, reference being had to the accompanying drawing, forming a part thereof.

Fig. 1 is a plan view of a power lawn mower, showing my new design;

Fig. 2 is a side elevational view and showing a driving engine in dotted lines;

Fig. 3 is a front elevational view; and

Fig. 4 is a rear elevational view.

The dominant features of my new design reside in those portions shown in full lines.

I claim:

The ornamental design for a power lawn mower, as shown and described.

CHARLES N. PHELPS.
